MULTI-ANGLE BRACKET

Gerald H. Sedo, West Covina, Calif., assignor to M & D Store Fixtures, Inc., a corporation of California
Filed Aug. 29, 1963, Ser. No. 305,290
5 Claims. (Cl. 248—242)

This invention relates to shelf supporting multi-angle brackets and particularly to such a bracket as is comprised of a single integral entity.

These brackets are widely used in store fixtures for supporting shelves at various angles on perforated vertical posts, the angle at which the bracket is supported on the post being determined by the operator's choice of one of several ways in which the bracket is adapted to interengage with edges of the perforations in said post.

In certain well-known brackets of this general type, such as that shown in U.S. Patent No. 3,089,675 issued to Gordon Lozier on May 14, 1963, the bracket may be selectively assembled on a post at any one of four different angles relative thereto. The assembly, in each instance, however, requires rotation of the bracket about a horizontal transverse axis after a certain one of a plurality of lugs formed rearwardly from the butt end of the bracket has been inserted through one of said perforations. This is to bring an upturned hook formed on the upper edge of said one lug into hooked relation behind the upper edge of said perforation while rotating another surface of the bracket into supported relation with the bottom edge of a lower perforation of said post and, finally bringing an abutment surface of the bracket against the outer face of the post below the last mentioned perforation.

In the patented bracket mentioned, these three accommodations of the bracket to the post must be differently performed in mounting the bracket on the post in the respective different inclinations of which it is capable. There is a degree of time consuming complexity thus involved in selecting the desired angle for each of a substantial number of brackets in changing the shelf angle in a large store fixture.

It is an object of the present invention to provide a multi-angle shelf bracket for use in store fixtures, the operation of which, in selecting the angle therefor, will be relatively simple and rapidly performed.

Another object of the invention is to provide a multi-angle shelf bracket having a choice between three angles, each of which may be selected merely by holding the bracket at the angle which has been selected, inserting the attaching lugs concerned horizontally rearwardly through the perforations located at the level where the bracket is to be mounted, and then bodily translating the bracket directly downwardly into its desired mounted position on the post.

A further object of the invention is to provide such a bracket which slightly resists such final downward movement of the bracket, requiring this to be driven into its completely assembled relation with said post, thereby preventing accidental dislodgement of said bracket from said position.

Yet another object of the invention is to provide such a bracket which, in each of its two most commonly used angles, where the shelf loads are heavy, the bracket has connection with the post over the area covered by a vertical column of three consecutive perforations in the post, while in its third angle, less commonly used and in which the shelf loads are relatively light, the bracket has connection over an area of two such consecutive perforations.

A still further object of the invention is to provide such a bracket in which a downward notch in an upper lug of the bracket is adapted to serve in holding the bracket in either of two different angles.

The manner of accomplishing the foregoing object as well as further objects and advantages will be made manifest in the following description taken in connection with the accompanying drawings, in which

5 FIG. 1 is a diagrammatic fragmentary elevational view of the butt end portion of a preferred embodiment of the present invention showing this mounted on a perforated vertical post with the bracket in steeply forwardly inclined relation with the post.

10 FIG. 2 is a view similar to FIG. 1 showing the bracket of the invention mounted on said post in horizontal or perpendicular relation therewith.

15 FIG. 3 is a view similar to FIG. 2 and illustrates the invention mounted on said post with said bracket in a slightly upwardly inclined relation with said post.

20 FIG. 4 is an enlarged detail view illustrating the X notch provided in the upper lug of the invention.

25 Referring specifically to the drawings, a multi-angle bracket 10 is shown therein as being mounted in each of three different positions on a perforated sheet steel channel post 11.

The bracket 10 is stamped out of a flat sheet of cold rolled steel of a thickness of about 14 gage and is made in different lengths running from 8 inches to 16 inches.

30 The bracket 10 has straight upper edge 12 which is provided with one or more notches 13 for accommodating reinforcing flanges which extend downwardly from shelves (not shown) and which the brackets 10 are provided for supporting with the shelves lying flat against the upper edges 12 of said brackets. The brackets 10 are of course normally used in pairs to support a shelf with one bracket under each end portion of the shelf.

35 Each bracket 10 has a butt end 14 from which three attaching lugs extend rearwardly, all of these lying of course in the flat plane of the bracket 10. These lugs are separately identified as upper lug 15, lower lug 16 and bottom lug 17.

40 These lugs are adapted to cooperate with a vertical row of perforations or slots 18 which are uniform in length and uniformly spaced vertically in a central web 19 of the channel post 11. The lugs 15 and 16 are so shaped and dimensioned and spaced vertically from each other that when the bracket 10 is held horizontally as shown in FIG. 2, but detached from the post 11 and is then moved longitudinally, which is to say horizontally, towards the post 11 with lugs 15 and 16 aligned with a vertically adjacent pair of slots 18, these lugs will pass entirely into said two slots.

45 It is now to be noted that lower edges of lugs 15 and 16 are provided with two pairs of downwardly facing notches one notch of each pair being in each of these lugs, with these notches being identified as the first pair of primary notches 25 and 26 and the second pair or secondary notches 27 and 28. Now it is to be noted that

50 after the lugs 15 and 16 have been translated horizontally through an adjacent pair of slots 18 with the bracket 10 held horizontally, all that remains to be done in order to mount the bracket on the post with the bracket disposed horizontally, is to translate, that is, move the bracket bodily downwardly, into the position into which it is shown in FIG. 2. Here we see that primary notches 25 and 26 in the base portions of the lugs 15 and 16 have received lower edges of the two slots 18 through which these lugs have been extended, so as to fix the bracket 10

55 horizontally on the post 11. The mounting of the bracket on the post is seen to be assisted by a notch 29 provided outwardly in the lower edge of bottom lug 17 engaging and embracing the lower edge of a third slot 18 which is disposed opposite the lug 17. Lug 17 also has another notch 30 located in a base portion of its lower edge.

60 The pair of secondary notches 27 and 28 provided in lower edges of lugs 15 and 16 are adapted to be employed

as shown in FIG. 3 in which these notches are caused to receive lower edges of adjacent slots 18 so as to mount the bracket 10 on the post 11 with the straight edge 12 of the bracket inclined upwardly with respect to the post.

It is now to be noted that the side edges 31 of secondary notch 27 have an hour glass shape which may also be referred to as an X-shape. This notch is thus shaped to facilitate its being alternately employed in connection with secondary notch 28 as shown in FIG. 3 for mounting the bracket 10 in upwardly inclined relation with the post 11, or to be employed as shown in FIG. 1 in which secondary notch 27 joins with primary notch 26 and base notch 30 in lug 17 to receive lower edges of three consecutive slots 18 and support the bracket 10 in steep downwardly inclined relation with the post as shown in this view.

The peculiar outline of secondary notch 27 permits this notch to make a close fit with the material of the post 11 disposed a substantial distance downwardly from the lower end of the slot in which the upper lug 15 is disposed for assembling the bracket 10 in either of the two angular positions shown for this in FIGS. 1 and 3. Another feature of notch 27 is that it provides converging edges 31 in the lower end portion thereof which approach a throat 32 formed by the narrowest portion of the notch and which are preferably so spaced that a slight driving of the bracket will be necessary to force this throat over the material of the post 11 just beneath the lower edge of the slot 18 in which lug 15 is being manipulated. The friction thus set up between the bracket 10 and the post is sufficient to prevent accidental removal of the bracket from the position in which it has been mounted on the post.

From the foregoing description it is believed manifest that the assembly of bracket 10 on post 11 in either of the three angular relations therewith, illustrated in FIGS. 1, 2 and 3, may be easily performed by unskilled labor so that a minimum amount of time and labor cost may be involved in modifying the shelf angles in various display equipment in which the brackets 10 are employed.

The claims are:

1. In a multi-angle bracket provided for attachment at different angles on a channel shaped sheet metal post having a vertical column of uniformly spaced slots formed therein, the combination of: a bracket arm adapted to support a shelf, said arm having a butt-end which is disposed adjacent said post when said bracket is mounted on the latter; upper and lower lugs extending rearwardly from said butt-end, said lugs being so dimensioned and so spaced vertically as to pass horizontally respectively entirely into a vertically spaced pair of said slots when said bracket is held horizontally and moved longitudinally butt-end first towards said slots, there being a first pair of notches individually located in the respective lower edges of said lugs which notches individually receive lower edges

of different respective ones of said slots when said bracket is translated downwardly with said bracket in a right angular relation with said post, and a second pair of notches individually located in the respective lower edges of said lugs which are adapted to individually receive lower edges of said respective slots when said bracket is translated downwardly with said bracket in a different angular relation with said post.

2. A bracket as recited in claim 1 wherein the notch in said upper lug of said second pair of notches is shaped to optionally receive the bottom edge of said upper slot when said notch in said lower lug of said first pair of notches is receiving the bottom edge of said lower slot when said bracket is translated downwardly with said bracket in a third and different angular relation with said post.

3. A bracket as recited in claim 2 wherein a bottom lug is provided to extend rearwardly from the butt-end of said bracket below said lower lug and is so spaced therefrom and so vertically dimensioned as to slide entirely into a third slot located immediately beneath said lower slot aforesaid, when said bracket is inclined downwardly relative to said post and translated longitudinally towards said post with said upper and lower lugs extending into said upper and lower slots, said bottom lug having a base notch in its lower edge which now receives the lower edge of said third slot when said bracket is translated downwardly to receive the lower edges of said upper and lower slots respectively in the notch of said second pair in the upper lug and the notch of said first pair in the lower lug.

4. A bracket as recited in claim 3 wherein said bottom lug has an outer notch in its lower edge which embraces the lower edge of said third slot when said bracket is assembled on said post, as aforesaid to form a right angle with said post.

5. A bracket as recited in claim 2 wherein said secondary notch in said upper lug has an X cross section for guiding said notch into embracing relation with a lower edge of one of said slots and for snugging the fit between said bracket and said post.
